UNITED STATES PATENT OFFICE.

JOSEPH F. PARKER, OF MOBILE, ALABAMA, ASSIGNOR, BY DIRECT AND MESNE ASSIGNMENTS, TO UNIVERSAL COMMUTATOR COMPANY, INC., A CORPORATION OF ALABAMA.

COMMUTATOR.

1,201,090.

Specification of Letters Patent. Patented Oct. 10, 1916.

Application filed November 23, 1915. Serial No. 63,108.

To all whom it may concern:

Be it known that I, JOSEPH F. PARKER, a citizen of the United States, residing at Mobile, in the county of Mobile and State of Alabama; have invented certain new and useful Improvements in Commutators; and I do hereby declare the following to be a full, clear, and exact description of the invention, such as will enable others skilled in the art to which it appertains to make and use the same.

My present invention relates to improvements in commutators, and consists more particularly in improvements and modifications of the device illustrated and described in my similarly entitled, co-pending application Serial No. 41127, filed July 21, 1915.

It is an object of the present invention to provide an improved commutator having all of the objects and advantages of my prior device illustrated in the application aforesaid, and which has been found to yield particularly excellent results on Ford automobiles; the several parts being arranged and constructed in such manner as to be adapted for application to the cam shaft of the motor without alteration or change therein; although it will be understood that the present invention may have a wider application and give good results on other types of cars.

Another object of the present invention resides in providing an improved commutator, the parts whereof will be inclosed in a casing surrounding the engine cam shaft or other engine driven shaft, and supported either therefrom or from the car chassis; said casing being provided with a removable front cover plate to give ready access to the interior of the casing from the front thereof, as found desirable in making adjustments and in substituting and renewing parts.

With these and other objects in view the invention consists in the novel details of construction and combinations of parts more fully hereinafter disclosed and particularly pointed out in the claims.

In the accompanying drawings forming a part of this application, and in which similar reference symbols indicate correspond-

ing parts in the several views: Figure 1 is a front elevational view, with the front cover plate partly broken away and showing the interior of the casing of an improved commutator constructed in accordance with the present invention. Fig. 2 is a central sectional view taken along the line 2—2 in Fig. 1; and Fig. 3 is a sectional view taken on the line 3—3 in Fig. 2.

Referring more particularly to the drawings, 1 designates a cam shaft, or other shaft, arranged to be driven from the internal combustion engine, and over which is mounted a casing 2 for inclosing the various parts of the improved commutator; and which casing is preferably supported from the chassis of the automobile in a manner not shown, as the same forms no part of the present invention, it being understood that such casing may be supported in any manner found desirable or necessary.

On the cam or other shaft 1 is fixed an eccentric 3 formed with a bearing 4 fitted on said cam shaft 1, and engaging a shoulder 20 on the shaft whereby the same is held to position. The eccentric 3 is also formed with a flange 21 embracing one side of a gear wheel 5 through a concentric opening in which said eccentric 3 is rotatably fitted. A plate 22 conforming substantially to the shape of the eccentric flange 21 is secured to the eccentric 3 by screws, or other means, 23, and embraces the opposite side of the gear wheel 5 for removably connecting said eccentric in place and to prevent possible disengagement therefrom during the operation of the device. This plate 22 is provided with a bearing 24, similar to the bearing 4, and extending oppositely therefrom, the same being perforated in registry with an opening in the cam shaft 1 to receive a pin 25, whereby the plate 22 and eccentric 3 are connected to rotate with the cam shaft 1.

Over the end of the cam shaft 1 is fitted a washer 26 formed with a flange 27 embracing the bearing 24, as advantageously shown in Fig. 2, and for positively preventing the pin 25 from accidental removal from engagement with the bearing 24 and cam shaft 1. The end of the cam shaft is threaded to 100

receive a nut 28, which is screwed up against the washer 26 and binds the several parts against the shoulder 20 of said cam shaft in a manner which will be apparent from an inspection of Fig. 2.

- The casing 2 is advantageously substantially cylindrical, as shown, and the front peripheral edge thereof is enlarged and threaded, as indicated at 29, to removably receive the enlarged and threaded edge 30 of a disk cover plate 31, through which convenient access may be had to the interior of the casing for adjustment of the parts, or for the removal and replacement of the same. 10
On the cover 31 is a central forwardly projecting boss 32, hollow within to receive the end of the cam shaft 1 and parts thereof, and formed with straight outer faces which may be hexagonal, as shown, to provide a 15
nut for engagement by the fingers or a wrench or other tool, whereby the cover may be readily removed and replaced.

The teeth on the gear wheel 5 engage complementary teeth on an internal gear 6 mounted within the casing 2, and over which the gear wheel 5 is adapted to roll as the cam shaft 1 is rotated. Adjacent the internal gear 6, in the casing 2, is also located a ring 7 of insulating material, wherein 25
are embedded a plurality of contact plates 8 corresponding in number to the number of cylinders of the engine. The contact plates 8 are here shown to be four in number, and are supported flush with the inner 30
surface of the insulating ring 7 by the binding post screws 9. On the screws 9 are threaded the usual nuts 10 and 11, between 35
which the leads to the sparking devices are clamped.

- 40 A drum 12 is secured in any suitable manner to the gear wheel 5, and is provided with a slotted rim for slidably receiving contact blocks 13, supported on the outer free ends of springs 15, secured by rivets or other suitable means 16 to the interior of the rim of said drum. The contact blocks are thus held normally projected, as will clearly appear from an inspection of Fig. 3, and the same are supported to yield when brought 45
50 into engagement with the corresponding contact plates 8.

The circuit may be completed from the contact blocks 13 through the metallic springs 15 and drum 12 to the cam shaft 1, or other circuit connections may be employed to complete the circuit, as may be found desirable or necessary in practice. 55

- The casing 2, as disclosed in Fig. 1, is provided with the usual arm 17 for connection by the spark control lever for shifting said casing in a manner and for a purpose well understood. 60

The gear wheel 5 and internal rack 6 are arranged to be so proportioned relatively,

that the gear wheel 5 will include a number of teeth extending over one-third of its periphery corresponding to the number of teeth embraced within a quarter of the internal rack 7. This arrangement will operate to bring the three contact blocks 13 shown, successively into engagement with the four contact plates 8; said blocks 13 being yieldingly pressed against the plates by the springs 15, as shown in Fig. 3, and which will insure a good contact even after 75 the contact blocks have been worn away to a great extent.

It is obvious that those skilled in the art may vary the details of construction and arrangements of parts without departing from the spirit of my invention, and therefore I do not wish to be limited to such features except as may be required by the claims.

I claim:

1. In an improved commutator of the character described, the combination with the motor cam shaft, of a casing fitted thereover, a series of concentrically arranged contact plates supported within said casing and in electrical connection with the sparking devices of the motor, an internal gear arranged in said casing adjacent said concentric series of contacts, an eccentric fitted on said cam shaft, a gear wheel having a concentric opening snugly receiving said eccentric, a drum secured to rotate with said gear wheel and having slots in the periphery thereof, spring means mounted within said drum, and a plurality of contact blocks yieldingly mounted on said spring means and arranged to slidably project through the slots in said drum for successively engaging said series of contact plates as the drum revolves, substantially as described. 95

2. An improved commutator including an engine-driven shaft, an eccentric on said engine-driven shaft, a gear wheel mounted over said eccentric, a casing, an internal gear within said casing arranged in mesh with said first-named gear wheel, an insulating ring mounted in the casing to one side of said internal gear, contacts embedded in said insulating ring and in electrical connection with the sparking devices of the engine, a drum secured to rotate with said gear wheel, and contact blocks on said drum for successively engaging the contact plates in said insulating ring, substantially as described. 110

3. In an improved commutator of the character described, the combination with the engine cam shaft, of a casing supported thereabout, an insulating ring in said casing, series of concentric contact plates embedded flush in said ring and in electrical connection with the motor sparking devices, an internal gear disposed adjacent said insulating ring, an eccentric mounted to rotate 125

with said cam shaft, a gear wheel fitted over said eccentric and in mesh to roll around within said internal gear, a drum supported to rotate with said gear wheel, a series of spring-pressed contact blocks carried by said drum for successively engaging said contact plates, a removable front cover

plate threaded into said casing, and a hollow boss on said cover plate for fitting the end of the cam shaft, substantially as described. 10

In testimony whereof, I affix my signature.

JOSEPH F. PARKER.
